CONTAINER

Walter A. Gueffroy, San Francisco, Calif., assignor to American Can Company, New York, N. Y., a corporation of New Jersey

Application December 16, 1939, Serial No. 309,668

1 Claim. (Cl. 220—1)

The present invention relates to containers or cans and has particular reference to a permanently deformable section for indicating spoilage of the contents in the can.

Perishable products such as, for example, frozen foods when packed in cans are subject to spoilage and fermentation when not constantly maintained under proper refrigeration. Fermentation of the product creates considerable pressure in the can and may sometimes burst the can if not detected soon enough.

The present invention contemplates providing a permanently deformable section in the can which may be inflated by the internal gases of fermentation to visibly indicate the condition of the product and which will readily show that such inflation has taken place even though the section has been punctured and the gases have escaped.

An object, therefore, of the invention is the provision of a sheet metal can having a deformable section wherein excessive pressure created within the can will permanently expand the deformable section beyond repair and thereby visibly indicate the condition of the contents of the can even though the expanded section has been punctured with the consequent escape of the pressure.

Another object is the provision in such a can of a deformable section wherein a thin permanently deformable metallic disc is secured over a vent hole in a wall of the can so that internal pressures will expand and permanently stretch the disc out of shape so that it will visibly indicate the pressure condition in the can and so that it cannot be pressed down again even if it has been purposely punctured to relieve the pressure, without visibly showing that such a fraudulent act has been practiced.

Numerous other objects and advantages of the invention will be apparent as it is better understood from the following description, which, taken in connection with the accompanying drawing, discloses a preferred embodiment thereof.

Referring to the drawing:

Figure 1 is a side elevation of a filled can embodying the instant invention, the upper portion of the can being broken away and shown in section;

Fig. 2 is an enlarged fragmentary sectional view of the upper end of the can shown in Fig. 1, the view showing in detail the construction of the deformable section of the can;

Fig. 3 is a sectional view of the upper portion 55

of the can in Fig. 1, the view showing the deformable section in an inflated condition; and

Fig. 4 is a view similar to Fig. 3 and showing how the deformable section may rupture under excessive inflation or pressure.

As a preferred embodiment of the instant invention the drawing illustrates a sheet metal container which is adapted to contain perishable foods. Such a can preferably includes a cylindrical body 11 having top and bottom closure members 12, 13 respectively secured thereto in suitable seams 14 such as the conventional double seam shown in the drawing.

15 The top closure member 12 is formed with a preferably circular shaped sunken panel 16 (Fig. 2) having a flat bottom wall section 17 which is pierced with a single vent hole 18. The bottom wall section 17 merges into a surrounding panel side wall section 19 which extends up into the top closure wall. These panel side walls 19 are slightly curved to form an annular recess 21.

20 The panel 16 contains a thin circular metallic disc 22 which constitutes the deformable section of the can. This disc is preferably made of aluminum or may be made of any other metal which readily bends or stretches. The disc lies flat against the panel bottom wall section 17 on the outside of the can and over the vent hole 18. The outer edges of the disc are preferably hemmed as indicated by the numeral 23. These hemmed edges fit tightly within the annular recess 21 in the panel side walls 19 and are secured in place with solder 24 or other suitable cementing material. This disc thus hermetically seals the vent hole 18.

25 When an internal pressure is created in the can, such as for example, by the spoilage and fermentation of the can contents, the pressure gases thus emitted escape from the can by way of the vent hole 18. The escaping gases exert their pressure against the metallic disc 22 and thereby inflate it into the outwardly bulged condition shown in Fig. 3. The metallic disc stretches to 30 permit this inflation and is thereby permanently deformed beyond repair. In this inflated condition the disc visibly indicates the pressure condition within the can and the can thereupon should be rejected.

35 40 45 50 If the inflated disc is fraudulently punctured to permit escape of the gases therefrom, the disc will nevertheless remain in its distorted condition. Even when pressed down flat against the can top, the once distorted disc will unduly wrinkle and clearly show that such fraudulent action has been

practiced and that the can at one time had been subjected to an internal pressure condition.

If sufficient pressure is created within the can before being noticed the deformable disc 22 may rupture or blow out as shown in Fig. 4. Such excessive pressure may even break the solder hold on the hemmed edge of the disc and cause a rupture along this edge. In any case the excess pressure will break through the metallic disc and thereby permanently destroy it as well as visibly indicate that such a pressure condition once existed in the can.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A container having a deformable section for indicating spoilage of the contents, which com-

prises a body member, a closure member secured to an end of said body member, said closure member having a substantially central sunken panel section defined by a peripheral side wall terminating at its lower portion in an annular recess, the bottom defined by said wall being substantially flat, said panel section also having a centrally disposed vent hole therein, and a normally flat thin sheet metal deformable element disposed over said vent hole on the outside of said container in close engagement with said sunken panel section, the outer periphery of said deformable element having a hemmed portion of double thickness engaging said annular recess and tightly soldered to the peripheral wall of said sunken panel section, the central portion of said deformable element being adapted to be pressed outwardly by pressure vapors emitted from the container contents through said vent hole as a result of spoilage and permanently deformed from its normal flat state to visibly indicate such spoilage condition.
